UNITED STATES PATENT OFFICE.

FRANK WALTER HOWARD, OF BROOKLYN, NEW YORK, ASSIGNOR TO
XENOPHON STOUTENBOROUGH, OF BROOKLYN, NEW YORK.

PUMP FOR FLUID-TANKS.

SPECIFICATION forming part of Letters Patent No. 694,645, dated March 4, 1902.

Application filed May 31, 1901. Serial No. 62,539. (No model.)

To all whom it may concern:

Be it known that I, FRANK WALTER HOWARD, a citizen of the United States, residing at the borough of Brooklyn, city and State of New York, have invented an Improvement 5 in Pumps for Fluid-Tanks, of which the following is a specification.

My invention relates to an improved pump for fluid-storage tanks especially adapted for 10 use with automobiles and other motor-vehicles and from which the feed-tanks of such vehicles are periodically filled.

My invention is also applicable for fluid-storage tanks for store use or for use in private dwellings and from which vessels, such 15 as lamps, may be readily filled; and the object of my invention is to provide a vapor-tight tank of few parts and one readily accessible and in which the parts are altogether 20 removable.

In carrying out my invention I provide a single removable cap forming a support for the barrel of the pump-plunger and for the discharge-pipe and packings at all the joints 25 and an adjustable discharge-pipe and an automatic valve in the head of said pipe normally seated to prevent escape of vapor and the effect of a back pressure.

In the drawings, Figure 1 is a vertical section representing my improved devices, together with the top and bottom portions of the tank. Fig. 2 is a plan of the operative and removable parts. Fig. 3 is a cross-section and inverted plan of the removable cap 35 at the line $x-x$ of Fig. 1. Fig. 4 is a sectional plan at $y-y$ of Fig. 1, and Fig. 5 is a sectional plan at $z-z$ of Fig. 1.

The tank a , of sheet metal, may be of any desired form. To an opening in this tank I 40 securely fasten by solder a flanged collar b , interiorly threaded. The removable cap c is provided with a substantially flat top, and a threaded flange c' is cored out on the under side to provide circular intermediate flanges, and the threaded flange c' screws into the flanged collar b , there being a packing 2 between the flat opposing faces of the parts to assist in forming a vapor-tight joint. Integral 45 with this removable cap c is a threaded

flange c^2 . The barrel d and the discharge-pipe h are received into the intermediate flanges on the under side of the removable cap and they are securely soldered thereto, and said barrel and discharge-pipe are each provided with a hole 1 near their point of connection with the cap. 50

The barrel d and discharge-pipe h extend downward from the removable cap through the tank to the bottom of the tank, and they are surrounded and connected with a case g 60 of tubular form, which embraces both of said parts, and which case is provided with a bottom plate g' , having an opening, and valve-plate 3, closing the same.

Within the barrel d is the plunger e and 65 plunger-rod f , and within the discharge-pipe h is an adjustable discharge-pipe i , having a packing i' around the same at the lower end to close the opening between the discharge-pipe and the adjustable discharge-pipe i , so 70 that as between these parts no fluid can pass no matter what the vertical position of the auxiliary discharge-pipe i may be with reference to the discharge-pipe h , as it is possible to raise and lower the adjustable pipe i 75 for the discharge of the fluid as may be desired. Upon the upper end of the adjustable discharge-pipe i I provide a head comprising a nozzle k and a valve-pocket k' , and from the nozzle k extends a pipe 4 to a feed-tank or for delivering fluid into a vessel. A seat is formed within this head at the base of the nozzle and the valve-pocket and at the upper end of the adjustable discharge-pipe 80 for a ball-valve 5. This valve is preferably 85 of metal, and being of some weight normally rests upon its seat. Around the pipe i and screwing into a recess in the upper surface of the removable cap c is a nut 6 of a packing-gland, whereby the passage of the pipe i 90 through the said cap is closed to the escape of fluid and also to the escape of vapor.

I provide a screw-cap l , interiorly threaded and screwing upon the threaded flange c^2 and the washer 7, between the under surface of 95 the cap l and the upper end of the barrel d . The plunger-rod f passes through the washer 7 and through the screw-cap l , and the upper

surface of the screw-cap is recessed to provide a packing-gland, and a nut 8, surrounding the plunger-rod *f*, screws into this recess to compress the packing and form a tight joint around the plunger-rod to prevent the escape of fluid and vapor.

The upper end of the rod *f* is provided with a handle 9, and the vertical upward movement of said rod *f* and plunger *e* draws the fluid from the tank into the case *g* and barrel *d* through the valve 3, and the downward movement of the said rod *f* and plunger *e* closes the valve 3 and forces the fluid up the discharge-pipe *h* and the adjustable pipe *i*, lifting the valve 5 from its seat into the pocket *k'* and escaping by the nozzle *k* and pipe 4. As soon as the movement of the plunger *e* ceases the ball-valve 5 returns to its seat, preventing the escape of vapor and the effect of any back pressure, and the holes 1 in the barrel *d* and discharge-pipe *h* maintain a balance of the vapor-pressure as between the tank and the inner portions of the barrel and the discharge-pipe with the movement of the parts. From this structure it will be observed that the case *g* is smaller in diameter than the threaded flange *c'* of the cap and that all the parts are connected to the removable cap *c* and that by unscrewing the cap *c* from the flanged collar *b* all the parts may be removed from and taken out of the tank. This facilitates the manufacture of the device, lessens the number of joints, and localizes any possible escape of fluid or vapor. Besides, both the pump and the discharge are adjacent to one another and of simplified form.

I do not herein lay any claim to the special structure of the case *g*, its valve 3, and the connection thereto of the barrel *d* and discharge-pipe *h* in themselves.

I claim as my invention—

1. The combination with the tank and the flanged collar connected thereto, of a removable cap adapted to be connected to the flanged collar, a pump device, a discharge-pipe and an adjustable discharge-pipe all connected to the said removable cap and extending in part from the cap down into the tank and upwardly from the cap outside of the tank, and a case of tubular form surrounding and secured to the lower ends of the pump device and discharge-pipes, substantially as set forth.

2. The combination with the tank and flanged collar, of a removable cap having a threaded flange adapted to be connected to the flanged collar, said removable cap being provided with flanges *c'*, 10 and 11 upon opposite sides of the cap and intermediate to the diameter of the threaded flange of the cap, a barrel and discharge-pipe connected to said cap and extending down into the tank, an adjustable discharge-pipe vertically movable in the main discharge-pipe and having a packing-gland in the cap, a plunger and plunger-rod within the barrel, a cap sur-

rounding the plunger-rod and screwing to the removable cap and a packing-gland in said cap around the plunger-rod, substantially as set forth.

3. The combination with the tank and flanged collar, of a removable cap having a threaded flange adapted to be connected to the flanged collar, said removable cap being provided with flanges upon opposite sides, a barrel and discharge-pipe connected to said cap and extending down into the tank, an adjustable discharge-pipe vertically movable in the main discharge-pipe and having a packing-gland in the cap, a plunger and plunger-rod within the barrel, a cap surrounding the plunger-rod and screwing to the removable cap and a packing-gland in said cap around the plunger-rod, a handle upon the upper end of the plunger-rod for operating the same, a head upon the upper end of the adjustable discharge-pipe and the valve therein normally seated at the upper end of said discharge-pipe to prevent escape of vapor and the effect of back pressure, substantially as set forth.

4. The combination with the tank and flanged collar, of a removable cap having a threaded flange adapted to be connected to the flanged collar, said removable cap being provided with flanges upon opposite sides, a barrel and discharge-pipe connected to said cap and extending down into the tank, an adjustable discharge-pipe vertically movable in the main discharge-pipe and having a packing-gland in the cap, a plunger and plunger-rod within the barrel, a cap surrounding the plunger-rod and screwing to the removable cap and a packing-gland in said cap around the plunger-rod, and a case surrounding the lower ends of the barrel and the discharge-pipe within the tank and having an opening in the bottom of the case and a valve adjacent thereto, substantially as set forth.

5. The combination in a pump device for fluid-tanks with the tank and a flanged collar connected thereto, of the removable cap *c* having a threaded flange *c'* for connection with the flanged collar, a packing 2 between the adjacent faces of the cap and collar and said cap provided with circular flanges, a barrel connected to one flange and a discharge-pipe connected to the other flange, an adjustable discharge-pipe passing through the cover, said cover having a recess providing a packing-gland and a nut 6 screwing into the said recess and extending around the adjustable discharge-pipe, a threaded flange *c'* rising from the removable cap and forming a substantial continuation of the barrel, a cap interiorly threaded and screwing upon the said flange, a washer 7 between the said parts, said screw-cap having a recess forming a packing-gland and a nut 8 screwing therein and extending around the plunger-rod of the pump, substantially as set forth.

6. In a pump for fluid-tanks, the combina-

tion with a removable cap and an adjustable discharge-pipe extending through the same, of a head upon the upper end of said discharge-pipe comprising a nozzle and integral valve-pocket and provided within at the base of the said nozzle and valve-pocket with a valve-seat at the upper end of the said pipe, and a ball-valve adapted to seat thereon and

be moved up into the valve-pocket when the fluid is discharged, substantially as set forth. ¹⁰

Signed by me this 16th day of May, 1901.

FRANK WALTER HOWARD.
